LOUIS T. BULLEY, OF NEW HAVEN, CONNECTICUT, ASSIGNOR TO C. COWLES & COMPANY, OF NEW HAVEN, CONNECTICUT, A CORPORATION OF CONNECTICUT.

CONTROLLING MECHANISM FOR WINDOW-REGULATORS.

1,338,485.

Specification of Letters Patent. Patented Apr. 27, 1920.

Application filed October 13, 1919. Serial No. 330,373.

To all whom it may concern:

Be it known that I, LOUIS T. BULLEY, a citizen of the United States, residing at New Haven, county of New Haven, State of Connecticut, have invented an Improvement in Controlling Mechanism for Window-Regulators, of which the following is a specification.

This invention relates to the class of window regulators illustrated and described in Letters Patent No. 1,245,189, granted to me November 6, 1917, in which the window is raised and lowered by an operating shaft and is automatically locked in any position in which it may be left by rotation of the shaft, and the present invention has for its object to provide controlling mechanism especially adapted for use with this class of regulators in which the construction is simplified, is light, durable and noiseless, and in which the cost is reduced to the minimum as the parts may be pressed out from sheet metal.

With these and other objects in view I have devised the novel window regulator controlling mechanism which I will now describe, referring to the accompanying drawing forming a part of this specification and using reference characters to indicate the several parts.

Figure 1 is a front elevation showing my novel controlling mechanism mounted on a carrying plate;

Fig. 2 a rear elevation corresponding therewith;

Fig. 3 a section, on an enlarged scale, on the line 3-3 in Fig. 1, looking in the direction of the arrows;

Fig. 4 a section on the line 4-4 in Fig. 3, looking in the direction of the arrows;

Fig. 5 a similar view, showing a position of the parts after the operating shaft has nearly completed a clockwise rotation, and

Fig. 6 is a rear elevation with the retaining plate removed, the point of view being at line 6-6 in Fig. 3, looking in the direction of the arrows.

10 denotes the operating shaft which is provided with a handle 11 and is mounted to 50 rotate in a hub 15 which in turn is mounted to rotate in a hole in carrying plate 16. 17 denotes a ratchet which is secured to carrying plate 16 by rivets 12. 14 denotes a sprocket wheel and 18 a disk which carries pawls 19 having backwardly extending

lugs 20 which pass through a cutaway portion of disk 18, indicated by 21, and are adapted to engage the teeth of the ratchet. Hub 15, sprocket wheel 14, and disk 18 are connected together by rivets 13 and are 60 adapted to oscillate on the shaft as a unit. 22 denotes a longitudinally movable pawl tripping plate having a relatively large central opening 23, through which the shaft passes, and 24, pins extending from the disk which engage radial slots 25 in the tripping plate and connect the tripping plate with the disk and limit the longitudinal movement of said plate. At right angles to slots 25 are enlargements of opening 23 to provide shoulders 26 which are adapted to be engaged by the ends of a cross pin 27 in the shaft. Pawls 19 are pivoted to the disk at approximately their midlength and the tail of each pawl is engaged by one arm of 70 a spring 28. These springs are coiled at their midlength about pins 29 extending from the disk, the other arms of said springs bearing against pins 30 on the tripping plate. The function of these springs is to 75 normally move the tripping plate out of operative position, that is backward away from the pawls, and to throw the pawls into engagement with the teeth of the ratchet. The parts on the front of the carrying plate 80 are inclosed in a casing 31 which is secured to the carrying plate. 32 denotes a cover plate at the back which is secured to the carrying plate by a screw passing through spacing plates 33, 34 and 35. 90

36 denotes the chain, one end of which is secured to the window, not shown, the other end being attached to a spring controlled drum, indicated by dotted lines in Fig. 2. The chain is adapted to be wound on the 95 drum, and from the drum passes upward over the sprocket wheel and then downward through a guide 37 to the window. The portion of the chain passing over the sprocket wheel is retained in place by means of a 100 curved plate 38 which forms a guide for the chain before it passes into guide 37.

Supposing the window to be lowered, to raise it the handle would be rotated in the clockwise direction. The normal position of 105 the parts would be substantially as shown in Fig. 4, although it is not essential that the disk and tripping plate be in the exact position shown, said parts would, however, be locked through the engagement of the 110

pawls with a tooth of the ratchet, which is fixed. The first effect of rotation of the shaft is to cause the left end of the cross pin, as seen in Fig. 4, to engage one of the 5 shoulders 26 and raise the tripping plate, which lifts the pawls and throws them out of engagement with the ratchet. The tripping plate and pawls will remain in the position relatively to each other that is shown 10 in Fig. 5 so long as rotation of the shaft continues. In Fig. 5 the shaft and parts carried thereby have made nearly a full rotation from the position shown in Fig. 4. During the raising movement of the window 15 the chain will be wound on the drum and the controlling spring for the drum will be unwound. The instant the operator releases the shaft, springs 28 will act to move the tripping plate from the relative position 20 shown in Fig. 5 to that shown in Fig. 4 and will cause the pawls to engage opposite sides of a tooth of the ratchet, thus locking the window, in any position in which it may be left, so that it cannot be moved in either 25 direction except by rotation of the shaft. It will of course be understood that the drum controlling spring was wound by the previous lowering of the window. In practice this spring is so adjusted as to provide an 30 effective counter-balance for the window.

If the window was left in a partly raised position and it is desired to raise it more or to entirely close it, the operation would be as before.

35 Should it be required to lower the window from either a wholly closed or a partly closed position, the shaft would be rotated in the counter-clockwise direction and the lifting of the tripping plate to disengage 40 the pawls from the ratchet tooth with which they were engaged would be effected by the right end of the cross pin, as seen in Fig. 4, instead of by the left end as before. So far as the present invention is concerned, the operation is practically the same in raising or 45 lowering the window. The shaft is turned in one direction to raise it and in the other direction to lower it. The drum controlling spring is wound by the lowering of the window and effectively counterbalances it so 50 that but little force is required to raise it. When the window is being lowered the chain will of course pass downward in the guide which prevents it from buckling.

55 Having thus described my invention, I claim:

1. A mechanism of the character described comprising a rotatable shaft, a sprocket wheel and a disk fixed to each other and oscillatable on the shaft, a fixed ratchet, pawls carried by the disk and adapted to engage the ratchet, a pawl tripping plate, springs acting to move the tripping plate out of operative position and to cause the pawls to engage 60 the ratchet, and a cross pin in the shaft

by which the tripping plate is actuated when the shaft is turned in either direction.

2. A mechanism of the character described comprising a rotatable shaft, a sprocket wheel and a disk fixed to each other and oscillatable on the shaft, a fixed ratchet, pawls carried by the disk and adapted to engage the ratchet, a spring controlled pawl tripping plate and an operating connection between the shaft and the tripping plate. 75

3. A mechanism of the character described comprising an operating shaft, a sprocket wheel loosely mounted thereon, a fixed ratchet, a disk connected to the sprocket wheel and rotating therewith, pawls carried by the disk and engaging the ratchet, a longitudinally movable tripping plate having an opening through which the shaft passes and shoulders, a cross pin in the shaft adapted to engage either shoulder and springs secured to the disk and acting to throw the tripping plate out of operative position and the pawls into engagement with the ratchet. 80

4. A mechanism of the character described comprising an operating shaft having a cross pin, a sprocket wheel loosely mounted on the shaft, a fixed ratchet, a disk loose on the shaft and connected to the sprocket wheel, pawls carried by the disk and adapted to engage the ratchet, a tripping plate 85 having shoulders adapted to be engaged by the cross pin, and springs acting to throw the tripping plate out of operative position and the pawls into engagement with the ratchet. 90

5. A mechanism of the character described comprising an operating shaft, a sprocket wheel loosely mounted thereon, a fixed ratchet, a disk loose on the shaft but connected to the sprocket wheel, pawls carried by the disk and adapted to engage the ratchet, a tripping plate having an opening through which the shaft passes, springs acting on the tripping plate and on the pawls, and an operating connection between the shaft and the tripping plate, whereby rotation of the shaft will cause the tripping plate to disengage the pawls from the ratchet. 105

6. A mechanism of the character described comprising an operating shaft, a sprocket wheel loosely mounted thereon, a fixed ratchet, a disk loose on the shaft and connected to the sprocket wheel, pawls carried by the disk and engaging the ratchet, a spring controlled tripping plate, and an operating connection between said shaft and said plate whereby rotation of the shaft will actuate said plate against the power of the springs. 115

7. A mechanism of the character described comprising an operating shaft, a sprocket wheel loosely mounted thereon, a fixed ratchet, a disk having pins, said disk being loose on the shaft and connected to the 120

sprocket wheel, pawls carried by the disk and engaging the ratchet, a longitudinally movable tripping plate having radial slots engaged by the pins and an opening having 5 shoulders, springs acting on the tripping plate and the pawls, and a cross pin in the shaft adapted to engage either shoulder, rotation of the shaft imparting longitudinal movement to the tripping plate and rotary 10 movement to said plate, the disk and the sprocket wheel.

8. A mechanism of the character described comprising an operating shaft, a sprocket wheel loosely mounted thereon, a fixed 15 ratchet, a disk having pins, said disk being loose on the shaft and connected to the sprocket wheel, pawls carried by the disk and engaging the ratchet, a longitudinally movable tripping plate having radial slots 20 engaged by the pins, springs acting on the tripping plate and the pawls and an operating connection between the shaft and the tripping plate.

9. A mechanism of the character described 25 comprising an operating shaft, a sprocket wheel loose thereon, a fixed ratchet, a disk loose on the shaft and having a cutaway, pawls carried by the disk and having lugs which pass through the cutaway and engage 30 the ratchet, a tripping plate, springs acting on the tripping plate and the pawls, and an operating connection between the shaft and the tripping plate.

10. A mechanism of the character described 35 comprising an operating shaft, a sprocket wheel loose thereon, a fixed ratchet, a disk loose on the shaft and connected to the sprocket wheel, pawls pivoted to the disk and and engaging the ratchet, a spring 40 controlled tripping plate and an operating connection between the shaft and the tripping plate.

11. A mechanism of the character described 45 comprising an operating shaft, a sprocket wheel loosely mounted thereon, a longitudinal movable tripping plate, a connection between the shaft and the tripping plate whereby the latter is rotated, and means for locking the sprocket wheel against

rotation in either direction, rotation of the 50 shaft causing the tripping plate to release the locking means.

12. A mechanism of the character described comprising an operating shaft, a sprocket wheel loosely mounted thereon, a 55 fixed ratchet, a disk loose on the shaft and connected to the sprocket wheel, spring controlled pawls carried by the disk and engaging the ratchet, a spring controlled tripping plate, an operating connection between the 60 shaft and the tripping plate, and a pin and slot connection between the tripping plate and the disk.

13. A mechanism of the character described comprising an operating shaft, a 65 sprocket wheel loosely mounted thereon, a fixed ratchet, pawls engaging said ratchet, a disk loose on the shaft by which the pawls are carried, a tripping plate, a connection between the shaft and the tripping plate 70 whereby the latter is moved longitudinally and is caused to rotate on the shaft, and a connection between the tripping plate and the disk.

14. A mechanism of the character described 75 comprising an operating shaft, a sprocket wheel loosely mounted thereon, a ratchet, a disk loose on the shaft, pawls carried by the disk and engaging the ratchet, a tripping plate having a pin and slot connection with the disk, and an operating connection between the shaft and the tripping plate, whereby the pawls are disengaged 80 when the shaft is rotated in either direction.

15. A mechanism of the character described 85 comprising a carrying plate, a hub mounted to rotate therein, a shaft mounted to rotate in the hub, a ratchet fixed to the carrying plate, a disk, a sprocket wheel, said sprocket wheel, hub and disk being connected together and rotating as a unit, pawls 90 carried by the disk and engaging the ratchet, a spring controlled tripping plate, and an operating connection between the shaft and the tripping plate. 95

In testimony whereof I affix my signature.

LOUIS T. BULLEY.
